Primary Examiner — Derrick E Holland*Assistant Examiner* — Janice Patyk(74) *Attorney, Agent, or Firm* — Seager, Tufte & Wickhem LLP(57) **CLAIM**

The ornamental design for a cosmetics dispenser, as shown and described.

DESCRIPTION

FIG. 1 is a perspective view of a cosmetics dispenser, showing our new design;

FIG. 2 is a front view thereof, the rear, left, and right views being the same;

FIG. 3 is a top view thereof, shown in enlarged scale;

FIG. 4 is a bottom view thereof, shown in enlarged scale; and,

FIG. 5 is a perspective view thereof, shown with a cap thereon.

The broken lines in the Figures illustrate the portions of the design that form no part of the claimed design.

1 Claim, 5 Drawing Sheets(56)
